UNITED STATES PATENT OFFICE

101,844

DESIGN FOR A BED SACK OR SIMILAR ARTICLE

Florence Weinberg, New York, N. Y.

Application August 8, 1936, Serial No. 64,298

Term of patent 3½ years

To all whom it may concern:

Be it known that I, Florence Weinberg, a citizen of the United States of America, residing in Manhattan, county of New York and State of New York, have invented a new, original, and ornamental Design for a Bed Sack or Similar Article, of which the following is a specification, reference being had to the accompanying drawing, forming part thereof, wherein,

The design is characterized by the stitched pattern on the body of the jacket giving a quilted appearance to the garment, in combination with the stand-up collar above the shirred yoke, as shown.

I claim:

The ornamental design for a bed sack or similar article, substantially as shown and described.

FLORENCE WEINBERG.
